(57) CLAIM

The ornamental design for a multiple electronic device reorienting support, as shown and described.

DESCRIPTION

FIG. 1 is a perspective view of a multiple electronic device reorienting support showing our new design in a first arrangement;

FIG. 2 is a front elevational view;

FIG. 3 is a rear elevational view;

FIG. 4 is a left side elevational view, the right side elevational view being identical thereto;

FIG. 5 is a top plan view;

FIG. 6 is a bottom plan view;

FIG. 7 is a perspective view of the multiple electronic device reorienting support showing the design in a second arrangement;

FIG. 8 is a front elevational view;

FIG. 9 is a rear elevational view;

FIG. 10 is a left side elevational view, the right side elevational view being identical thereto;

FIG. 11 is a top plan view;

FIG. 12 is a bottom plan view; and,

FIG. 13 is a front elevational view of the multiple electronic device reorienting support showing the design in a plurality of arrangements.

Any broken lines or broken line illustration of environmental structure in the drawings are not part of the design sought to be patented.
